UNITED STATES PATENT OFFICE.

WALTER E. COFFIN, OF CLEVELAND, OHIO, ASSIGNOR, BY MESNE ASSIGNMENTS, TO NATIONAL MALLEABLE AND STEEL CASTINGS COMPANY, OF CLEVELAND, OHIO, A CORPORATION OF OHIO.

TRANSITION COUPLER.

Application filed February 16, 1923. Serial No. 619,340.

To all whom it may concern:

Be it known that I, WALTER E. COFFIN, a citizen of the United States, residing at Cleveland, Cuyahoga County, Ohio, have invented new and useful Improvements in Transition Couplers, of which the following is a specification, reference being had to the accompanying drawings, in which:—

Fig. 1 shows a plan of a car coupler embodying my invention; Fig. 2 is a side elevation thereof; Fig. 3 is a horizontal section through the coupler head; and Figs. 4 and 5 show the knuckle in side elevation and rear elevation, respectively.

My invention relates particularly to transitional coupling mechanism and is designed to provide means for permitting cars fitted with automatic couplers to be coupled with cars equipped with couplers of other types, such as of the draw-hook connection type. To this end I have provided a transition or emergency knuckle which may be readily substituted for the ordinary knuckle in a Master Car Builders' type of coupler and is secured to the coupler head by the ordinary pivot pin. My improved knuckle is provided with attaching means for the transition link and may be swung into locked or knuckle thrown position by the usual locking and opening mechanism when so attached to provide for or take up slack required for connecting with or disconnecting from a coupler of the draw-hook connection type. My invention also comprises the various features which I shall hereinafter describe and claim.

Referring to the drawings, 2 indicates a coupler of the Master Car Builders' type such as is shown in the application of Arthur J. Bazeley, Serial No. 481,468, filed June 30, 1921, but, obviously, may be any coupler head conforming to the lines of the M. C. B. or the standard D coupler types.

The knuckle 3 comprises a suitably formed knuckle with a tail 4, a hub portion 5 and a link attaching part 6, all of which are made as an integral casting. The knuckle tail 4 is so formed as to fit within the particular design of coupler head with which the knuckle is to be used. The hub portion 5 is formed for reception of the usual knuckle pin 7, by which it is attached to the coupler ears 18, and may be provided with the pin protector lugs 8 or any other features which may be special to a particular coupler with

which it is to be used. Instead of being provided with the usual nose or pulling part as in the case of a standard knuckle, my improved knuckle has a link attaching part 6 apertured at 9 to carry a wrought or forged link 10, which lies in a substantially vertical plane, and on the longitudinal center line of the coupler. Attached to the link 10 is also a second link 11. The link 11 is intended to be passed over the draw-hook 12 of an opposing car. My improved knuckle 3 when attached to a coupler head as described is intended to be locked and opened by means of the ordinary locking and opening mechanism normally employed in the coupler, the lock being indicated as 13 and the opener 14.

To couple two cars together, equipped respectively with couplers 2 and 12, the lock 13 of the automatic coupler 2 is raised, which allows the transition knuckle 3 to swing open, thus providing slack in the chain which is ample to allow the link 10 to pass over the tip of the draw-hook 12. The knuckle 3 is then swung closed, taking up the slack in the links 10 and 11 and permitting the lock to drop, thus locking the knuckle. When so locked the buffers 15 on the cars are just brought into contact, as is shown in Fig. 1.

In uncoupling, the lock 13 is raised, and the opener 14 swings the transition knuckle 3 open, providing enough slack in the links 10 and 11 so that the link 11 can be unhooked from the draw-hook 12. In case of coupling on a curve, the buffers 15 on the inside of the curve may come in contact in such manner as to hold the coupler 2 and draw-hook 12 such a distance apart that the transition knuckle 3 can not be locked after the couplers have been connected by the links 10 and 11. In such a case, as the links 10 and 11 connect the cars together and the knuckle 3 is securely attached to the head 2 by means of the pivot pin 7 even when in open position, this connection permits the cars to be pulled off the curve onto a straight track with the transition knuckle 3 open. When the cars have reached a straight track the knuckle 3 may then be closed and locked.

In buffing, as the buffers 15 are compressed the links 9 and 10 are free to drop down or collapse out of the way of the draw-hook 12 and coupler 2. To prevent the

draw hook 12 from striking the forward face 16 of the knuckle under extreme buffing conditions the forward face of the knuckle is cut away and extends laterally toward 5 the guard arm 17 some distance to the rear of the forward face of the coupler ears 18, as is best shown in Figs. 1 and 3, so as to prevent the draw-hook 12 from striking the knuckle when under full buffing compression. 10

My invention may be readily applied to couplers of existing design and provides a transition knuckle of extremely rugged character which because of its large safety factor is sufficiently strong to withstand all 15 service stresses. The ease with which it may be substituted for the usual knuckle in a coupler whenever and wherever coupling with a coupler of a different type may be desired 20 is of great advantage.

The terms and expressions which I have employed are used as terms of description and not of limitation, and I have no intention, in the use of such terms and expressions, of excluding any mechanical equivalents of the features shown and described, or 25 portions thereof, but recognize that various structural modifications are possible within the scope of the invention claimed.

30 What I claim is:

1. In coupler mechanism, an automatic coupler having secured thereto a transitional coupling knuckle arranged to be held in transitional locked position by standard operating mechanism and secured to the coupler by the usual pivot pin, the said knuckle having its pulling part extending rearwardly into the recess in the buffering face of the coupler and having a vertically disposed aperture therethrough for reception of a pulling link, the said pulling link comprising means for attachment to a coupler of a different type. 40

2. In coupler mechanism, an automatic coupler head; a transitional coupler knuckle secured to the coupler by the usual pivot pin extending through ears on said coupler head and arranged to be held in transitional locked position by standard operating mechanism; the said knuckle carrying a coupling link free to swing in a vertical plane; all of 45

the knuckle, including its pulling portion, when in operative locked transitional position lying rearwardly of the forward portion of said coupler ears. 55

3. In coupler mechanism, an automatic coupler of the Master Car Builders' type having secured thereto a transitional coupler mechanism arranged to be held in transitional locked position by standard operating mechanism and secured to the coupler by the usual pivot pin, the knuckle having a pulling part extending forwardly from inside of the coupler buffering face and laterally from the inside face of the coupler ears, at right angles to the knuckle tail, the said extended part having a vertically disposed aperture for reception of a pulling link comprising means for attachment to a coupler of a different type. 60

4. In coupler mechanism, the combination with an automatic coupler of a transition knuckle, the said knuckle being secured to the said coupler by an ordinary pivot pin and being operated transitinally by an ordinary locking and opening mechanism, the forward face of the said knuckle being arranged at a distance to the rear of the forward faces of the coupler ears to prevent engagement by a coupler of a different type 70 during buffing. 75

5. In coupler mechanism, a combination with an automatic coupler of a knuckle pivoted thereto by an ordinary pivot pin and operated by ordinary locking and knuckle opening mechanism, and transition links carried by the said knuckle and arranged to intercouple with a coupler of the draw-hook connection type, the said knuckle having a pulling bearing with one of said links, the 80 said bearing being located a distance to the rear of the pivot pin and practically central with the center line of the couplers. 85

6. A transitional coupler knuckle comprising a hub portion having a pivot pin aperture; a tail portion; a locking portion; and a pulling portion displaced transversely from the hub and tail portions and connecting hub and locking portions and providing means for attachment to a coupler of a different 90 type. 95
